BRIDGE CABLE ANCHORAGE

Ralph W. Finke, Olympia, Wash., and Otto Rae Elwell, deceased, late of Olympia, Wash., by Bess Williams Elwell, Olympia, Wash., executrix

Application October 16, 1937, Serial No. 169,368

12 Claims. (Cl. 14—21)

The present invention relates to an improved anchorage for a multiple strand cable in which provision is made for anchoring and adjusting the tension of each strand individually.

The invention is particularly adapted for anchoring bridge cables, although manifestly the cables can also be used for other purposes. Furthermore, the invention is also adapted for use in anchoring individual wires of strands or cables.

In building suspension bridges of comparatively short span it is desirable to make up the cable of preformed strands cut to uniform length and provided with end fittings in the factory. Each strand must be individually tensioned to be sure that it will carry its full share of the load. While in the main body of the cable the strands are compactly bundled together they must be splayed out at the anchorage to provide room for the end fittings and for the tensioning and anchoring means.

One object of the present invention is to provide a very simple and very compact anchorage in which the splay angle will be reduced to a minimum thereby keeping the maximum bend in any strand well within its elastic limits.

Another object of the invention is the provision of a universal connection between each strand and the anchorage providing for a straight forward pull of the bearing block against its pivot support in the anchorage and also providing for lateral adjustment of the strand socket to prevent any bending of the strand at the point of connection with its socket.

A further object of the invention is to provide an anchorage in which the parts will be readily accessible for tensioning the strands in such sequence as to prevent skewing and unbalanced strands. In order to accomplish this result it is desirable to arrange the strands in vertically spaced horizontal tiers, and in anchoring the strands it is desirable to start with the bottom tiers to tension first the strands which lie directly on the saddle of the bridge after which the other tiers may be progressively tensioned and anchored. In each tier it is preferable to tension the middle strand or strands first and thereafter to tension the strands at each side thereof thereby maintaining a proper balance.

The present invention has for an object to provide an anchorage in which such order of procedure may be conveniently carried out.

Further objects and advantages of the invention will appear in the following description of a preferred embodiment and thereafter the nov-

elty and scope of the invention will be pointed out in the claims.

In the accompanying drawings:

Figure 1 is a view in side elevation of the approved anchorage assembly with a concrete abutment of the anchorage indicated fragmentally and in section and with one of the anchorage plates of the anchorage frame work broken away to show a side view of a strand socket and shoe and mounting therefor; 5

Fig. 2 is a top plan view of the anchorage frame showing the strand sockets and shoes of several strands mounted in position between adjacent anchorage plates;

Fig. 3 is a front view of the anchorage assembly taken on the line 3—3 of Fig. 1;

Fig. 4 is a longitudinal section on an enlarged scale of a strand socket and shoe taken on the line 4—4 of Fig. 1; and

Fig. 5 is a detailed perspective view of a strand 20 socket and shoe shown disconnected.

The cable 10 illustrated in the drawings is made up of nineteen strands 11, as shown clearly in Fig. 3. Obviously the number of strands may be varied as desired and the anchorage correspondingly modified. The strands are nested together in the main body of the cable, as shown in Fig. 1, and are passed through a splay casting 12 which is preferably suitably grooved to conform to the outer contour of the cable. The 30 grooves in the casting are preferably slightly flared toward the anchorage to permit the requisite splaying of the strands. 25

The strands adjacent the anchorage are preferably grouped in five vertically spaced rows, as 35 shown in Fig. 3, the middle row comprising five strands, the next adjacent rows four strands each and the top and bottom rows three strands each.

Each strand is provided with an end fitting consisting of a strand socket member 14, and a 40 strand shoe 15. Each strand socket member comprises a tapered socket in which the strand may be permanently fixed by means well known in the art as, for instance, by brooming the end of the strand and embedding the same in a mass of solder or other suitable metal. Each strand socket member is provided with vertically spaced rearwardly extending arms 16 provided with pivot holes, as indicated. The forward portions of these arms are preferably of less width than the diameter 50 of the large end of the socket, as indicated at 17, to permit free lateral swinging movement of the strand socket member 14 within the anchorage frame, as clearly indicated in Figs. 2 and 3. The strand socket member is connected by a 55

pivot pin 18 to the strand shoe 15 and this pivot pin may be held in position by a cotter pin, if desired.

The strand shoe 15 comprises a horizontally arranged forward tongue 19 provided with a pivot hole to receive the pivot pin 18 and is tapered laterally toward the rear where it is enlarged vertically, as indicated at 20, to provide for a substantially rectangular slot 21 to receive the 10 pivot rod 22 upon which the strand shoe is mounted for sliding movement longitudinally and for pivotal movement in a vertical plane. Mounted within the slot is a bearing block 23 for cooperation with a pivot rod 22. The rear portion of 15 the strand shoe is of rectangular form and is widened laterally to provide a laterally extended abutment 24 for the bearing block. As disclosed clearly in Fig. 2, the forward end of the strand shoe is provided with parallel side faces having 20 a sliding fit engagement with the adjacent side plates 25 of the anchorage frame. U-shaped shims 26 are inserted between the bearing block and abutment 24 to hold the strand shoe 15 in the rearward position to which it has been adjusted by means of a threaded adjusting bolt 27 which is threaded in the rear end 24 of the strand shoe and bears against the bearing block 23. The upper and lower walls of the slot 21 are provided with parallel side faces to accommodate a plurality of similar shims 26.

In connecting the strands to the anchorage frame, the lower row of strands may be tensioned and pulled to the rear by a block and tackle into a position in which the cooperating pivot rod 22 may be passed through the slots in the shoes connected to these strands. The adjustment of each strand is then effected by turning the adjusting bolt 27 which bears on the bearing block 23 thereby pulling the strand shoe toward the rear until the strand has been adjusted to the desired tension. The proper number of shims are then inserted between the bearing block and the rear end of the strand shoe after which the adjusting screw may be partially withdrawn. 40

The anchorage frame disclosed comprises six anchorage plates 25, the four plates in the center which support the pivot rod 22 for the upper row of strand shoes being of greater vertical dimension than the side plates.

50 The plates 25 of the anchorage frame may be secured together by L-shaped vertical bars 28 located to the rear of the pivot rods 22, spaced U-shaped bars 29 connecting the forward ends of the central plates and by oppositely facing spaced U-shaped bars 30 placed back to back and connecting the forward ends of the side plates to the adjacent plates. The U-shaped bars 30 extend below the anchorage frame proper to support the frame on a concrete anchorage, as indicated in Fig. 1. The anchorage frame is preferably also braced by the pivot rods 22 which for this purpose are provided with heads and nuts, as shown.

60 The rear ends of the plates 25 may be provided with holes 31 to receive a pivot rod 32 on which may be mounted anchorage links 33 suitably connected to and embedded in the concrete anchorage, as indicated. Each of the outside plates 25 may be provided with two vertically extending bars 34 reinforcing the walls of the holes in these plates and each of the inside plates may be faced with plates 35 to reinforce the holes in these plates.

65 By referring to the various figures of the drawings it will be noted that by the provision of a

universal joint which comprises a forward vertical pivot and rearward horizontal pivot, the plates of the anchorage frame may be spaced closely thereby reducing the transverse width of the anchorage frame to a minimum resulting in a very compact and rigid construction and also reducing the splay angle at the casting 12 to a minimum. As the strand shoes are provided with widened portions at their front ends engaging the plates of the anchorage frame, the bearing contact of the bearing block against the cooperating pivot rod will be uniform throughout the length of the block and rod. By providing the strand socket members with reduced portions, as indicated, free pivotal movement of the strand sockets is permitted without interference by the plates of the anchorage frame whereby each strand socket may adjust itself laterally to the direction of the strand to which it is secured to prevent any bending of the strand at the point where it is secured to the socket.

70 While a preferred embodiment of the invention has been shown and described it will be understood that this is to be taken as illustrative and not limitative and that the right is reserved to make various changes in form, construction and arrangement of parts without departing from the spirit and scope of the invention as set forth in the claims.

What is claimed is:

1. A multiple strand cable anchorage including spaced anchorage plates, a plurality of anchorage pivot rods extending transversely through said plates, strand shoes arranged between said plates and having transverse openings through which said pivot rods are passed, bearing members within said openings and engaging said pivot rods to accommodate strand angularity in one plane, and strand sockets connected to said strands and pivotally connected to said shoes to accommodate strand angularity in a plane at right angles to said first mentioned plane.

2. In a multiple strand cable anchorage, the combination of spaced anchorage plates, at least one pivot rod positioned transversely by said plates, strand shoes each arranged between said plates and having a transverse opening through which said pivot rod is passed and having side faces cooperating with the faces of adjacent plates, a bearing block in said opening, and means connected to the strand and pivotally mounted on the forward end of said shoe providing for pivotal movement of said means laterally of said shoe and plates.

3. In a multiple strand cable anchorage, the combination of spaced anchorage plates, at least one pivot rod positioned transversely by said plates, strand shoes each arranged between said plates and having a transverse opening through which said pivot rod is passed and having side faces cooperating with the faces of adjacent plates, a bearing block in said opening, means connected to the strand and pivotally mounted on the forward end of said shoe providing for pivotal movement of said means laterally of said shoe and plates, and means on said pivot rod cooperating with said plates to maintain the cooperative relation between the faces of said shoes and the faces of said plates.

4. Means for anchoring a strand comprising a strand socket and a strand shoe, a pivot connecting said strand socket and strand shoe for movement in one plane, said strand shoe being provided with an elongated opening extending trans-

versely thereof at right angles to the axis of said pivot to receive a pivot pin and bearing block for pivotally supporting said strand shoe for movement in a plane at right angles to said first mentioned plane, and a bearing block in said opening.

5. Means for anchoring a strand comprising a strand socket and a strand shoe, a pivot connecting said strand socket and strand shoe for movement in one plane, said strand shoe being provided with an elongated opening extending transversely thereof at right angles to the axis of said pivot to receive a pivot pin and bearing block for pivotally supporting said strand shoe for movement in a plane at right angles to said first mentioned plane, a bearing block in said opening, and an adjusting and tensioning screw mounted centrally in the rear end of said strand shoe and extending within said opening and against said bearing block.

6. Means for anchoring a strand comprising a strand socket and a strand shoe, a pivot connecting said strand socket and strand shoe for movement in one plane, said strand shoe being provided with an elongated opening extending transversely thereof in a direction at right angles to the axis of said pivot to receive a pivot pin and bearing block to support the strand shoe for movement in a plane at right angles to said first mentioned plane, a bearing block in said opening, and laterally extending shoulders on the rear end of said shoe providing an abutment for U-shaped shims for said bearing block.

7. Means for anchoring a strand comprising a strand socket and a strand shoe, a pivot connecting said strand socket and strand shoe for movement in one plane, said strand shoe being provided with an elongated opening extending transversely thereof in a direction at right angles to the axis of said pivot to receive a pivot pin and bearing block to support the strand shoe for movement in a plane at right angles to said first mentioned plane, a bearing block in said opening, laterally extending shoulders on the rear end of said shoe providing an abutment for U-shaped shims for said bearing block, and an adjusting and tensioning screw mounted centrally in the rear end of said shoe and extending into said opening against said bearing block.

8. Means for anchoring a strand between parallel plates of an anchorage frame comprising a strand shoe, a strand socket, a pivot connecting said socket to said shoe for movement in a plane transversely of said plates, said shoe having provision for mounting the same for pivotal movement in a plane parallel to said plates and guid-

ing faces on the sides of said shoe for cooperation with the faces of said plates, said guiding faces extending forwardly and rearwardly of the pivot between said socket and shoe for cooperation with the faces of said plates.

5

9. The combination in an anchorage for multiple strand cables, of an anchorage frame comprising spaced parallel plates, strand connectors each comprising a front member secured to a strand, a rear member, a pivot connecting said front member to said rear member for movement of said front member in a plane transversely of said plates, said pivot being located rearwardly of and adjacent to the forward edges of said plates, and a pivot between said rear member and said plates for movement of said rear member in a plane parallel to said plates, said rear member being provided with side faces located forwardly of said second mentioned pivot, slidably engaging the faces of adjacent plates, and said front member having its forward strand connecting portion extended beyond the forward ends of said plates and having its side walls cut away to clear said plates to permit of extended pivotal movement of said front member transversely of said plates.

25

10. An anchorage frame comprising spaced plates, a pair of cables arranged transversely of said plates, end fittings on said cables, means pivotally supporting said end fittings between said plates, and means located forwardly of said supporting means spacing said end fittings and providing for unrestricted individual pivotal movement of said end fittings.

30

11. In combination with an anchorage frame, a pair of cables, shoes for said cables pivoted on said frame for pivotal movement in parallel planes, sockets secured to said cables, means pivotally connecting said sockets to said shoes for pivotal movement in a plane at right angles to the planes of movement of said shoes, and means spacing said shoes at the pivotal connections between said sockets and shoes.

35

12. In combination with an anchorage frame, a pair of cables, sockets secured to said cables, shoes pivotally supporting said sockets for movement in a common plane, means pivotally supporting said shoes on said frame for movement in planes at right angles to said first mentioned plane, and means spacing said shoes and providing for relative movement of said shoes in said second mentioned planes.
